(57) **CLAIM**

The ornamental design for an ultralight semi-automatic pistol slide, as shown and described.

DESCRIPTION

FIG. 1 is a front right perspective view of an ultralight semi-automatic pistol slide showing my new design; FIG. 2 is a front view thereof;

FIG. 3 is a back view thereof;

FIG. 4 is a top view thereof;

FIG. 5 is a bottom view thereof;

FIG. 6 is a left view thereof;

FIG. 7 is a right view thereof;

FIG. 8 is a front left perspective view thereof;

FIG. 9 is a back right perspective view thereof; and,

FIG. 10 is a back left perspective view thereof.

The evenly broken lines depict portions of the slide that form no part of the claimed design.
